UNITED STATES PATENT OFFICE.

CHARLES H. WESTCOTT, OF SENECA FALLS, NEW YORK.

TOY BUILDING-BLOCK.

SPECIFICATION forming part of Letters Patent No. 319,764, dated June 9, 1885.

Application filed September 15, 1884. (No model.)

To all whom it may concern:

Be it known that I, CHAS. H. WESTCOTT, of Seneca Falls, in the county of Seneca, and in the State of New York, have invented certain new and useful Improvements in Toy Building-Blocks; and I do hereby declare that the following is a full, clear, and exact description thereof, reference being had to the accompanying drawings, in which—

10 Figure 1 is a perspective view of one of my blocks as preferably constructed. Fig. 2 is a like view of a modification of the same. Figs. 3 and 4 are perspective views of two of the many forms in which said blocks may be combined; and Figs. 5 and 6 are longitudinal sections of the blocks joined together, shown in Figs. 1 and 2, respectively.

Letters of like name and kind refer to like parts in each of the figures.

20 My invention relates to devices for the amusement of children, and has for its object an increase in the number of figures which may be produced by the combination of interlocking blocks; to which end said invention 25 consists, principally, in a toy building-block that is provided at each end with intersecting grooves and upon each side face with a raised panel, which at its ends forms shoulders that correspond in position to the bottoms of said 30 grooves and furnish end bearings for the engaging blocks, substantially as and for the purpose hereinafter shown.

It consists, further, in a toy building-block 35 which is provided at its ends with intersecting grooves and engaging-tongues, and within each side corner has a right-angled rabbet, substantially as and for the purpose hereinafter set forth.

It consists, finally, in a toy building-block 40 which is provided at each end with intersecting grooves and corresponding tongues, upon each side face has raised panels that constitute end bearings for engaging blocks, and within each side corner is provided with a 45 right-angled rabbet, substantially as and for the purpose hereinafter shown and described.

In the annexed drawings, A represents a block that has a general square form, and within each end is provided with four right-angled grooves, a, each of which is parallel with

one of the side faces and is separated therefrom by means of a tongue, a', that corresponds in thickness to the width of such groove and is adapted to fit into and be contained within any groove of another similar 55 block.

Within each side corner of the block A is formed a right-angled rabbet, a'', the sides of which are in a line with the inner sides of the grooves a, that intersect each other at such 60 corner, while upon each side face is formed a raised panel, a³, that at its ends a⁴ corresponds to and is in a line with the bottoms of the adjacent grooves.

In use one of the tongues a' of one block 65 A is inserted within a groove a of another block, and is pressed inward until its top bears against the bottom of said groove and the end of said first block abuts upon the shoulder a', formed by the contiguous end of 70 the panel a³ of said second block, in which position said blocks are locked together by the friction between the sides of said tongue and groove.

The corner rabbets a'' permit two blocks A 75 to be secured within adjacent intersecting grooves a of a third block, as shown in Fig. 3, while without such provision such arrangement of blocks would be impracticable, and the forms in which they could be combined 80 would be considerably lessened in number.

The shoulders a' render the joints between the blocks much firmer than would otherwise be the case, and enable said blocks to be more readily brought into line with each other; but, 85 if desired, the panel may be omitted, as shown in Fig. 2, without lessening the number of combinations of which said blocks are capable.

Having thus fully set forth the nature and 90 merits of my invention, what I claim is—

1. A toy building-block that is provided at each end with intersecting grooves and upon each side face with a raised panel which at its ends forms shoulders that correspond in 95 position to the bottoms of said grooves and furnish end bearings for the engaging blocks, substantially as and for the purpose shown.

2. A toy building-block which is provided at its ends with intersecting grooves and en- 100

gaging-tongues, and within each side corner has a right-angled rabbet, substantially as and for the purpose set forth.

3. A toy building-block which is provided at each end with intersecting grooves and corresponding tongues, upon each side face has raised panels that constitute end bearings for engaging blocks, and within each side corner is provided with a right-angled rabbet,

substantially as and for the purpose shown to and described.

In testimony that I claim the foregoing I have hereunto set my hand this 1st day of September, 1884.

CHARLES H. WESTCOTT.
